(57) **CLAIM**

The ornamental design for a baseball cap, as shown and described.

DESCRIPTION

FIG. 1 is a perspective view of a baseball cap, showing my new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof; and,

FIG. 8 is a bottom perspective view thereof.

The broken lines showing text within a depiction of a thought bubble in the drawings depict portions of the baseball cap that form no part of the claimed design. The remaining broken lines represent stitching, and are part of the claimed design.
